TOASTER

Lurelle V. A. Guild, Noroton, Conn., assignor to Westinghouse Electric Corporation, a corporation of Pennsylvania

Application December 13, 1954, Serial No. 33,528

Term of patent 14 years

(Cl. D81—10)

FIG.2.

FIG.1.

Fig. 1 is a view in perspective of a toaster showing my new design; and

Fig. 2 is a side elevation of the toaster shown in Fig. 1.

The dominant features of the design reside in the portions shown in full lines in the drawing.

The opposite side of the toaster, not in view, is substantially similar in appearance to the side shown. The opposite end of the toaster is generally similar in appearance to the end shown except that the handle slot is omitted.

I claim:

The ornamental design for a toaster, substantially as shown and described.
